UNITED STATES PATENT OFFICE.

JOHN S. MONAGHAN, OF ROCHESTER, NEW YORK, ASSIGNOR TO GERMAN-AMERICAN
BUTTON COMPANY, OF ROCHESTER, NEW YORK, A CORPORATION OF NEW YORK.

DESIGN FOR A BUTTON.

49,748.

Specification for Design.

Patented Oct. 10, 1916.

Application filed July 15, 1916. Serial No. 109,573. Term of patent 7 years.

To all whom it may concern:

Be it known that I, JOHN S. MONAGHAN, a citizen of the United States, and a resident of the city of Rochester, county of Monroe, State of New York, have invented a new, original, and ornamental Design for Buttons, of which the following is a specification.

My design is represented in the accompanying drawing, in which;

Figure 1 is a plan view. Fig. 2 is a side view. Fig. 3 is a vertical section through the center of Fig. 1.

The outer side edge of the button has the shape of the frustum of a cone, the base of which is flat. The upper face of the button is provided with a circular depression

of equal depth, the wall surrounding the depression having sloping sides diverging from each other toward the base, the top of the wall having a rounded surface. The edge of the base is slightly beveled.

I claim:

The ornamental design for a button substantially as shown and described.

In witness whereof I have hereunto set my hand at Rochester, in the county of Monroe and State of New York, this 12th day of July, 1916.

JOHN S. MONAGHAN.

In presence of—

MILTON NOYES,
MARGARET W. LARKIN.
